UNITED STATES PATENT OFFICE

CLINTON R. WILLIAMS, OF NEW YORK, N. Y.

FOUNTAIN-PEN HOUSING

Application filed March 16, 1927, Serial No. 175,689. Renewed March 22, 1930.

My invention relates to a device for housing the nib end of a fountain pen, when not in use. It is well known to all users of fountain pens that if allowed to lie on the desk with the nib uncovered, they become clogged from the drying of the ink in the nib and feeding means. This at times is very exasperating and often requires much time and manipulation to restore the proper flow of the ink in order to write.

I am aware that there is at present in use a protective cap to fasten frictionally or by screw threads over the pen nib when the fountain pen is carried on the person and this same type of cap is also being used as a desk fixture inverted and held in position by means of a collar or clip and the pen forced downwardly into it.

The general object of my invention is to provide a simple and inexpensive means of housing and unhousing the fountain pen nib. My invention obviates the necessity of groping for the small cap to enclose the nib end of the pen from the atmosphere and to require no more care in its operation than is required to lay the instrument on the desk.

My invention not only provides a useful article for the purposes hereinbefore outlined, but a device of simple construction, reliable in operation, inexpensive to make and highly ornamental in appearance.

The fountain pen housing comprises a base stand with support for the pen proper and a chamber for the automatic housing of the nib end of the pen. This chamber may take innumerable shapes. It is here constructed of two sections with the end wall of the support acting as the third wall of the chamber. The two side walls poised vertically have rests attached to the ends for the support of the pen nib end and which serve to automatically close the side walls of the chamber or housing upon placing the pen thereon. The removing of the pen from the supporting members automatically opens the housing, releasing the pen for use.

I have illustrated types of my invention in the accompanying drawings, wherein:

Figure 1 is a side elevation view showing the housing chamber closed with a portion of

the side wall broken away to show the pen properly supported and the nib housed therein.

Figure 2 is a plan view of Figure 1.

Figure 3 is a cross sectional view of Figure 55 1 at 3—3, showing the housing closed and the pen supported on the guide arms.

Figure 4 is a cross-sectional view similar to Figure 3, with the housing chamber walls open and the pen at the moment of contact 60 with the housing member guide.

Figure 5, shows a view similar to Fig. 3, but with the two closures sections standing open and with the fountain pen being deposited 65 in place to close the sections.

Figure 6 is a perspective view of one of the closure housing members with guide or means attached for holding the pen and moving the housing to open and closed positions.

Figure 7 shows a portion of Figure 6 in detail, as to the manner of fastening the guide or pen rest to the side wall of the housing.

Figure 8 is a variation of Figure 6, showing a side wall with one half of the end walls connected together.

Referring to the drawings, 1 is an ordinary fountain pen which is provided with a removable cap 2, for covering and protecting the pen nib 3, and its ink feeding means when the instrument is not in use and is carried in the pocket of the user. When the instrument is to be used for writing, the cap 2, is removed from the pen nib end of the holder and is usually temporarily mounted on the butt end of the holder, as shown herein. 85 When my device is used to house the pen nib, the ordinary protecting cap 2 remains mounted on the butt end of the holder, so as to leave the pen nib free and ready for instant use.

In the construction of my device as shown in Figures 1 to 8, inclusive, 4 is a base having at one end suitably spaced upright members 5 and 6, between which are disposed a cooperating pair of closure members 7 and 8, which are constructed and arranged to open and close with respect to each other. These door-like members 7 and 8, are mounted to swing on their lower ends by means of a hinge connection comprising a strip 9, 100

which passes loosely through slots 10 and 11 in the respective members, the strip being held fast by a screw 12, secured in the base 4. The upright members 5 and 6 may 5 serve as end walls for the closure members 7 and 8, thereby forming a closed cap or housing chamber when said closure members are in closed contact with each other. The formation of the end or upright walls referred to, is accomplished by means of a reinforcement or shoulder 13—13, placed on the housing side of said walls. The shape and size of the fountain pen housing may be varied as desired, the only requisite being that one end of the housing should conform 10 as closely to the shape of the pen as possible to avoid improper and unprotected exposure to the atmosphere, for the purpose outlined. The material which may be used in making the housing may be glass, rubber, celluloid, casein, metals such as tin, bronze, silver or other substances. The housing members 7 and 8 are here made of thin metal, shaped at the top to the contour of the pen and gradually 15 becoming straight at the base and poised pivotally in horizontal grooves 14—14 of the foundation member 4, so that when not in use the walls automatically and instantly open for the reception of the pen.

30 The grooves 14—14 are here cut out of the foundation member 4 inside the line of equilibrium of the plane of the closure members 7 and 8, and extending from 13 to 13. At the base of each closure member 7 and 8 are 20 small slots 10 and 11 cut therein to receive a small strip fastened to the foundation 4, by a screw 12 for the purpose of keeping the closure members 7 and 8 in place if jarred. The closure members 7 and 8 have at 25 15—15 slight apertures cut therein to receive lugs 17—17 of pen supporting arms 16—16, made with ends elevated and grooved to fit the pen and securely fastened within the closure walls 7 and 8 and sufficiently below the under- 30 side of the curved portion thereof, to permit the pen to be seated thereon. The supporting arms 16—16 are not placed in alignment as it is intended they should overlap and when the pen comes in contact with the open arms 16—16 the weight of the pen causes 35 the crossed arms to open and the closure walls to close. When the pen is removed the side closure walls fall outwardly to an open position, due to the top of the said walls being outside the line of equilibrium. This operation, so obvious, can also be accomplished by means of slight weights or springs 40 neither of which are here shown in the drawings.

45 If desirous of making the housing chamber of but two parts without using uprights 5 and 6, the detailed construction of the side walls as shown in Figure 8 may be used instead of the simpler form herein before explained and shown in Figure 6. Thus in

Figure 8, the end walls 16—16 are an integral part of the side walls 7 and 8.

It is readily seen that my invention is capable of a great number of variations in construction, both as to ornamental design 70 as well as mechanical operation thereof and I do not limit myself narrowly to the form which I prefer and have shown in the accompanying drawings.

From the foregoing, it will be seen that 75 my improvements provide a handy and cheap device which can be used in an office or household as a desk article and that it serves to encourage the use of fountain pens, since many people have heretofore refrained from 80 using fountain pens for the reason that in order to keep them in operative condition ready for instant use, the instrument when not in use had to have the pen nib covered with a detachable cap in order to keep the 85 ink in the pen nib and feeding means from drying up and then placed securely in a position with the pen nib projecting upwardly, so that the pen nib would not bleed.

What I claim is:

1. In a construction for covering the pen-nib end of a fountain pen, a suitable housing provided with a movable closure which opens upon removal of the pen-nib, means for moving said closure into closed position and 90 said means being engaged and actuated by the insertion of the fountain pen in the housing to thereby close the closure.
2. In a construction for covering the pen-nib end of a fountain pen, a suitable housing 95 for receiving the pen-nib and provided with a movable closure, means for opening and closing said closure, said means being automatically operated to close said closure by the insertion of the fountain pen in said 100 housing and the engagement of said means by the fountain pen and also to automatically open by gravity upon the withdrawal and disengagement of the fountain pen.
3. In a construction for covering the pen-nib end of a fountain pen, a suitable housing 105 provided with a movable closure which automatically assumes open position by its own weight upon withdrawal of the pen-nib, and which assumes closed position by the counterpoise weight of the pen-nib upon its insertion in place therein.
4. In a construction for housing the pen-nib end of a fountain pen, a housing casing 110 formed in sections mounted so as to open from and close on each other and normally standing open and adapted to close and house the pen-nib when the latter is deposited within said sections and the weight of the fountain pen imposed thereon.
5. In a construction for housing the pen-nib end of a fountain pen, a housing casing 115 composed of two swinging sections mounted so as to open from and close on each other and normally assuming open positions, said 120

sections being provided with pen-nib receiving racks for engagement with the pen-nib, and said sections being adapted to be moved into closed positions when the pen-nib is placed in said racks.

5 Signed at New York city, in the county of New York and State of New York, this 11th day of March, A. D. 1927.

CLINTON R. WILLIAMS.
